UNITED STATES PATENT OFFICE.

JOSEPH ANTONIO GUARINO, OF WESTERLY, RHODE ISLAND.

GUN.

1,079,855.

Specification of Letters Patent. Patented Nov. 25, 1913.

Application filed January 8, 1913. Serial No. 740,878.

To all whom it may concern:

Be it known that I, JOSEPH ANTONIO GUARINO, a citizen of the United States, residing at Westerly, in the county of Washington and State of Rhode Island, have invented new and useful Improvements in Guns, of which the following is a specification.

The invention relates more particularly to 10 the class of guard trigger boxes for firearms.

The primary object of the invention is the provision of a device of this character in which the trigger or triggers of a firearm when moved from operative position may be 15 concealed so as to avoid the accidental working of the triggers and thereby causing a premature discharge or firing of the gun.

Another object of the invention is the provision of a gun attachment which can be 20 readily swung to closed or open position and when in closed position will conceal the trigger or triggers to avoid the premature firing of the gun and thus prevent the possibility of accidents therefrom and when the attachment is in open position the gun can 25 be fired in the usual well-known manner.

A further object of the invention is the provision of a gun attachment which is extremely simple in construction, thoroughly 30 reliable and efficient in its purpose, and inexpensive in manufacture.

With these and other objects in view, the invention consists in the construction, combination and arrangement of parts as will be 35 hereinafter more fully described, illustrated in the accompanying drawing and pointed out in the claim hereunto appended.

In the drawings: Figure 1 is a fragmentary side elevation of a gun showing the attachment in position for concealing the trigger of the said gun. Fig. 2 is a similar view showing the attachment in open position to permit the gun to be fired as usual. Fig. 3 is a fragmentary vertical longitudinal sectional view through the gun and attachment, the latter being in the position shown 45 in Fig. 1.

Similar reference characters indicate corresponding parts throughout the several 50 views in the drawings.

Referring to the drawing by numerals, 5 designates the stock of a gun of any ordinary well-known construction, 6 the breech,

7 a portion of the barrel, 8 the trigger guard, and 9 the trigger which is pivoted at 10 so 55 that the same can be swung forwardly and upwardly from operative position into the breech 6 for the concealing of the same when the gun is being carried in the hand, the concealing of the trigger 9 being effected in 60 a manner presently described.

Mounted upon the breech 6 at the rear end of the guard and working within the latter is a concaved box-like body 10' provided at its rear end with a pintle sleeve 11 through 65 which is passed a pintle 12, the same being also passed through a pintle sleeve 13 formed on a leaf hinge section 14 which is suitably fixed to the breech, whereby the said box-like body 10' can be swung forwardly and up- 70 wardly into the position shown in Fig. 1, or swung downwardly and rearwardly to the position shown in Fig. 2 of the drawing.

On the swinging of the box-like body 10' forwardly and upwardly after the trigger 9 75 has also been swung forwardly and upwardly within the breech the said body 10' is engaged with a catch 15 which locks it in closed position so as to conceal the trigger and prevent the same from swinging to operative position, and in this manner it will be impossible for the trigger to be actuated and thereby obviate the premature or accidental discharge of the gun. The box-like body 10' when closed can be manually released and 85 swung to open position so that the trigger can be operated for the firing of the gun in the usual well-known manner.

From the foregoing it is thought that the construction and manner of operation of the 90 device will be clearly understood, and therefore a more extended explanation has been omitted.

What is claimed is:

The combination with a gun having firing 95 mechanism including a trigger swingingly supported for movement from operative to inoperative position within the breech of the gun, of a bearing formed on the breech of the gun rearwardly of the path of movement of the trigger, a trigger guard comprising a dished member having a pintle sleeve at one end and a nib at its opposite end, a pivot passed through the pintle sleeve and engaging the bearing for swingingly 100 connecting the guard thereto whereby it may 105

be moved to a position for concealing the trigger when located within the breech of the gun, and a latch member pivoted to the breech of the gun forwardly of the path of movement of the trigger and movable into engagement with the nib for sustaining the guard in a position for concealing the trigger and adapted to be moved for releasing

the guard whereby it may be moved out of the path of movement of the trigger.

In testimony whereof I affix my signature in presence of two witnesses.

JOSEPH ANTONIO GUARINO.
